UNITED STATES PATENT OFFICE

EMORY DAUGHERTY HECOX, OF COLUMBUS, OHIO

APPARATUS FOR PRODUCING MUSICAL TONES AND SOUNDS

Application filed July 25, 1930. Serial No. 470,663.

My invention relates to improvements in music and sound producing instruments in which the sound waves caused by singing or playing are utilized to provide a musical or sound accompaniment for the singing or playing. My invention also discloses a relatively simple musical system whereby automatic harmonious musical accompaniment is possible.

10 The object of this invention is to provide a system and instrument, whereby an operator, singing a song, playing on a musical instrument, or making sounds, may provide his own musical or sound accompaniment, based 15 on the tones sung or played, or the sounds made. Such a system and instrument will eliminate the necessity of having an accompanist for an artist. For the novice, will provide a means of giving a complete musical 20 rendition when he only has the ability to play a single note, for instance on the piano.

A brief description of the device will further show its objects and possibilities, following which I will explain several forms of the 25 invention in connection with the accompanying drawings.

A simple arrangement of my patent would be a microphone with a source of current, a 30 modulation transformer, an electro-magnet in the magnetic field of which are a number of reeds or tuning forks having varying natural frequencies. When a tone is sounded into the microphone, all the reeds or tuning forks receive the vibrations, but that one' 35 coinciding in natural frequency with the frequency of the tone sounded, vibrates more fully than the others. The vibration of this reed or tuning fork actuates a circuit which causes one or more tones to be sounded on any 40 musical instrument. In another arrangement this vibration actuates a circuit to which is attached one or more oscillating devices of audio frequencies, which oscillators produce corresponding vibrations in another circuit. 45 The latter circuit leads to an amplifying device, which causes the tones so produced from the oscillators to be sounded from a loud speaker, together with the original tone or note sung or played into the microphone. 50 By suitable switching means, different combi-

nations of tones may be provided for the different tones when they are to be sung or played in the different musical keys.

Several forms of the invention are illustrated in the accompanying drawings. Figures 1, 2 and 3 are diagrammatic views of three different embodiments of my invention, (Figure 1 being partly in perspective). Figure 4 is a diagrammatic view of the switching means and connections necessary for singing or playing in one key and within one octave. Figure 5 is a diagrammatic view of the metronome switching device which may be used in connection with the system and instrument.

In Figure 1, A is a microphone; X is a battery or other source of current; B is a transformer with 1 and 2 the primary and secondary respectively; C is a selector device of audio frequencies, 3 the electro-magnet adjacent to which are steel reeds 4, 5, 6, 7 and 8 of varying natural audio frequencies; 9, 10, 11, 12 and 13 are contacts normally close to associated contacts on reeds 4, 5, 6, 7 and 8 but not making contact therewith when the reeds are at rest; D is a locking relay to be actuated by reed 5 and contact 10. The device requires one of these locking relays for each of the reeds but for the sake of simplicity I am only showing one. 15 is the locking relay electromagnet; 14 is a contact normally making contact with an associated contact on armature 17; 16 is a contact normally close to an associated contact also on armature 17, but not normally making contact therewith; 18 is a second armature in connection with electromagnet 15; 19, 20, and 21 are contacts which are normally close to associated contacts on armature 18 but not making contact therewith; E is a switching metronome further described in Figure 5; F is a battery or other source of current; G is a piano each key of which has an electromagnet so applied as to operate the key when current is induced in the electromagnet.

The operator singing or playing tones into the microphone A causes electrical vibrations to be set up in the primary 1 of transformer B, and by induction the same vibrations are

set up in secondary 2 of transformer B, causing electrical and resultant magnetic vibrations in electromagnet 3. These vibrations will then set the steel reed, whose natural frequency coincides with the tone frequency sounded into microphone A, into vibration. Assuming that reed 5 is so vibrated, then contact 10 is brought into contact with its associated contact on reed 5 and current flows from battery F through metronome E, through reed base and reed 5 to contact 14, through armature 17 of locking relay D, through the coil of electromagnet 15 and back to battery F. This current so flowing causes armature 17 to be drawn toward electro-magnet 15, thereby closing contact 16 and its associated contact on armature 17, and simultaneously breaking contact 14 and causing armature 17 to stay against electromagnet 15 until the current from battery F is broken off. At the same time as electromagnet 15 pulls armature 17 towards it, armature 18 is also likewise pulled towards it and contacts 19, 20, and 21 are closed with their associated contacts on armature 18. The closing of these contacts causes the three electro-magnets 22, 23, and 24 to play their respective notes on piano G. The switching metronome E operates at any desired frequency, so that at the end of its beat it releases locking relay D. If the same tone is still being sounded into the microphone A upon the return of the metronome into its next beat, the locking relay will again lock causing the three keys to be again sounded on the piano G and the metronome will again release locking relay D at the end of the second beat.

In this particular arrangement any type of instrument which translates sound vibrations into electrical vibrations, may be used for microphone A and transformer B. Any type of resonance meter may be substituted and modified readily to serve the function of tone selector C. The locking relay D and metronome E may be of any type, or may be omitted altogether as they are not essential to the operation of the system or instrument. Any suitable type of instrument may be substituted for piano G.

In Figure 2, A is a microphone, X is a battery or other source of current; B is a transformer, 1 is the primary and 2a, 2b, and 2c are the secondaries; C is a selector device of audio frequencies, 3a, 3b, and 3c are coils in magnet relation to tuning forks 4, 5, and 6 respectively, the tuning forks having varying natural audio frequencies; 9, 10, and 11 are contacts normally close to associated contacts on one leg of tuning forks 4, 5, and 6 respectively, but not making contact therewith; D1, D2, and D3 are locking relays of which 15a, 15b, and 15c are the electro-magnets; 14a, 14b, and 14c are contacts normally making contact with associated contacts on armature

17a, 17b, and 17c respectively; 16a, 16b, and 16c and 19a, 19b, and 19c and 20a, 20b and 20c are other contacts normally close to associated contacts on armatures 17a, 17b, and 17c respectively, but not making contact therewith; E is a switching metronome; F is a battery or other source of current; H1, H2, and H3 are electron tube oscillators; J is a transformer, of which 35a, 35b, and 35c are primaries connected to electron tube oscillators H1, H2, and H3 respectively; 38 is also a primary of transformer J; 36 is the secondary of transformer J in inductive relation to primaries 35a, 35b, 35c, and 38; K is an amplifying device and L is a loud speaker.

The operator, singing or playing tones into microphone A, causes electrical vibrations to be set up in the primary 1 of transformer B, and by induction the same vibrations are set up in the secondary of transformer B which cause the same vibrations in the coils 3a, 3b, and 3c connected to the secondaries 2a, 2b, and 2c respectively. The vibrations so set up in coils 3a, 3b, and 3c, which are in magnetic relation to tuning forks 4, 5, and 6 respectively, will cause one of the tuning forks whose natural frequency coincides with the tone sounded into microphone A, to vibrate freely. Assuming that this frequency coincides with the natural frequency of tuning fork 4, tuning fork 4 will vibrate and bring the contact 9 into contact with its associated contact on tuning fork 4. The closing of these contacts causes current to flow from battery F, through metronome E, through tuning fork 4 and contact 9 to contact 14a, which is normally closed with its associated contact on armature 17a, through armature 17a and coil 15a back to battery F. This current so flowing, causes armature 17a to be drawn against electro-magnet 15a, thereby closing contact 16a and its associated contact on armature 17a and locking armature 17a against electro-magnet 15a as long as current flows from battery F, at the same time breaking the connection at contact 14a and simultaneously closing contacts 19a and 20a with their associated contacts on armature 17a. The closing of contacts 19a and 20a causes electron tube oscillators H3 and H2 to oscillate. The oscillations of these electron tube oscillators are by inductance transferred from primaries 35b and 35c into secondary 36 of transformer J. The original tone sung or played into microphone A is induced into secondary 39 of transformer B and is transferred to the secondary of transformer J through primary 38. The original tone and the two new tones from oscillators H2 and H3 are then sent into the input of amplifier K, there amplified and sounded in loud speaker L.

In this particular arrangement, any type of instrument which translates sound vibrations into electrical vibrations may be used

for microphone A and transformer B. Any type of resonance meter may be substituted and modified readily to serve the functions of tone selector C. The locking relays D1, 5 D2, and D3 and metronome E may be of any type to serve the purpose or may be omitted altogether as they are not essential to the successful operation of the instrument. Any type of oscillator may be used instead of the 10 electron tube oscillator shown, such as mercury arc oscillator, audio oscillator, impulse generator and any other known device giving the same results. Any number of oscillators may be connected for a given tone by 15 adding contacts to armatures 17a, 17b, etc. Any desired range of tones may be covered by adding additional tuning forks to the selector device.

In Figure 3, A is a microphone; X is a battery or other source of current; B is a transformer, with 1 the primaries and 2a, 2b, and 2c the secondaries; C is a selector device and oscillating device combined; 3a, 3b and 3c are coils in magnetic relation to tuning forks 4, 25 5, and 6 respectively which have varying natural audio frequencies; 9, 10, and 11 are contacts normally close to the associated contacts on one leg of tuning forks 4, 5, and 6 respectively, but not making contact therewith; 30 D1, D2, and D3 are locking relays of which 15a, 15b, and 15c are the respective electro-magnets. 14a, 14b, and 14c are contacts normally making contact with associated contacts on armatures 17a, 17b, and 17c respectively; 35 16a, 16b, 16c, and 19a, 19b, 19c, and 20a, 20b, 20c are other contacts normally close to associated contacts on armatures 17a, 17b, and 17c respectively, but not making contact therewith; E is a switching metronome; F is 40 a battery or other source of current; 40, 41, and 42 are field coils in magnetic relation to tuning forks 4, 5, and 6 respectively; 46, 47, and 48 are armature coils with their core magnets 49, 50, and 51 respectively, in inductive relation to ends of tuning forks 4, 5, and 6 respectively; condensers 63, 64, and 65 are in series with the armature coils 46, 47, and 48 respectively.

Coils 40, 41, and 42 are actuated through 50 contacts 19a, 19b, and 19c and 20a, 20b, and 20c respectively in the same manner as are oscillators H1, H2, and H3 by the same numbered contacts in Figure 2. These field coils 40, 41, 42 magnetize tuning forks 4, 5, 6 respectively, and their contacts 43, 44, 45 respectively, cause the tuning forks to vibrate in their natural frequencies setting up resultant oscillations in the resonant circuit composed of the armature coils 46, 47, and 48, 55 condensers 63, 64, and 65 and primary coils 35a, 35b, and 35c of transformer J. K is an amplifier and L is a loud speaker. The operation of the balance of the instrument coincides with the description given for Figure 2.

60 In Figure 4, I show a diagrammatic view

of a practical switching arrangement for changing the connections between the selector device and the oscillators as such changes are required for harmonies in the various musical keys. The switch will carry as many sets of 70 contacts as the musical range to be covered by the instrument. There may be twelve switches of the type shown, one for each key. Others may be added for spread chords, and various combinations or variations of chords 75 and high and low notes, as required. Additional switches may be provided which throw retardation coils in series with the electro-magnets 22, 23, etc. in Figure 1 or with oscillators H1, H2, etc. in Figure 2 thus obtaining the effect of runs and trills. In the switch diagram, I show a practical switching arrangement for all the notes on one octave, from C to B inclusive, when singing or playing in the key of C. In Figure 4, 71 to 82, 80 inclusive, are the contacts 19a and 20a etc. as shown in Figures 1, 2, and 3 as contacts of locking relays D, D1, D2, and D3. A is the master switch for the one key of C. The illustration shows the tumbler for Key of C 85 depressed and ready for operation. Wires 91 to 99 inclusive will lead to electro-magnets 22, 23, etc., in Figure 1, or to electron tube oscillators H1, H2, etc., in Figure 2 or to field coils 40, 41, etc., in Figure 3. In case contacts 91 are closed, as will occur upon the operation detailed for the locking relay which we will assume is the one operated when the tone is played or sung into the microphone, the leads marked E and G are then connected 90 therewith, through the switch A, causing their respective electro-magnets or oscillators to be put into operation as covered in the descriptions given for Figures 1, 2, 3. By adding additional contacts to armatures 17 95 or 18 of the locking relays D, D1, etc., and providing additional contacts and switch fingers to master switch A, any number of tones may be provided in the musical accompaniment. The switch shown is manually 100 operated. It may of course be operated by means of a remotely controlled locking relay, if operating conditions require.

In Figure 5, I disclose the metronome which may be used in connection with my invention. A represents an ordinary metronome. The source of current is connected at any point on segment 2. Swing switch arm 3 carries the current to the binding post and pivot 1 from segment 2 through a brush in 115 the bottom end of the switch arm. The connection from the metronome is made at binding post 1. The metronome swings the switch arm into positions 5 and 6 alternately, breaking the circuit at each swing, since it carries 120 the arm and brush contact on the end thereof past the end of metallic segment 2. The circuit is closed as long as the switch arm is on the segment.

This invention may take a very simple 125

form by the replacement of the audio frequency selector device in Figure 1 with a musical instrument, for instance a piano. Contacts 19, 20 and 21 would be located on the bottom of the piano key so that pressure upon the key would close them, thereby causing electro-magnets 22, 23 and 24 to play their respective notes on piano G. Another arrangement would replace the reeds of the audio frequency selector device with the piano keyboard, thereby operating the locking relay D with metronome E in the circuit, by having contacts 4, 5, 6, 7, and 8 on the piano keys and closing with their associated contacts 9, 10, 11, 12 and 13 when the various keys are depressed. In neither of these arrangements is microphone, C, battery X and transformer B required.

This arrangement may consist of a piano for operating purposes and another one for playing the accompaniment, or operation may be on the same instrument which plays the accompaniment. Another arrangement would consist of a control keyboard for the purpose of actuating the melody and accompaniment on the piano or other musical instrument. With such a control keyboard any number of adaptable musical instruments could be caused to play the melody and accompaniment merely by playing the melody itself on the control keyboard. With any of these arrangements it would be advisable to have a series of twelve master switches, such as the one pictured in Figure 4, so that the musical accompaniment would be proper for any key in which the melody might be played. If an operator desired to play a melody in the key of C, for instance, the switch for the key of C would be depressed or raised as the case might be to make the connections. This would connect to all the keys on the control board, chords which would be relative to the key of C. The basis for all the natural tones in a given key would be the chords of the tonic, the dominate and the sub-dominant. For other than natural or normal tones, appropriate chords would be used for accompaniment.

While I have illustrated several practical embodiments of my invention, modifications, substitutions and variations will occur to persons skilled in the art, and all such are included and considered to fall within the scope and spirit of my invention. In the appended claims it is intended to cover all the novelty that the invention may possess.

What is claimed is:

1. In a music producing system means whereby chords harmonious to a melody are automatically produced by the production of the melody.
2. In an instrument of the type set forth, means for receiving sound waves, a selector means for utilizing said sound waves so received as a means of causing other sound

waves to be sounded, the latter waves to provide harmonious chord accompaniment for the former sound waves.

3. In an instrument of the type set forth, means for receiving musical tone waves, a selector means for utilizing said musical tone waves so received as a means of causing other musical tone waves to be emitted from a music producing instrument, the latter musical tone waves to provide harmonious chord accompaniment for the former musical tone waves. 70

4. In an instrument of the type set forth, an audio frequency selector device, a switching metronome and a musical instrument having connections enabling it to be operated by 80 the frequency selector device.

5. In an instrument of the type set forth, means for receiving sound waves, a selector means for utilizing said sound waves so received as a means of causing other sound 85 waves to be sounded, the latter sound waves to provide musical accompaniment for the former sound waves.

6. In an instrument of the type set forth, means for receiving musical tone waves, a selector means for utilizing said musical tone waves so received as a means of causing other musical tone waves to be emitted from a music producing instrument, the latter musical tone waves to provide musical accompaniment for 95 the former musical tone waves. 90

7. In an instrument of the type set forth, a microphone, an audio frequency selector device, a plurality of locking relays, a switching metronome, a plurality of oscillating devices of audio frequencies, switching means for changing the relationship of the different frequency units of the selector device to the oscillating devices, an amplifier, a loud speaker, and a source of current. 100

8. In an instrument of the type set forth, a microphone, an audio frequency selector device, a plurality of locking relays, a switching metronome, a musical instrument in operative relation to the audio frequency selector device, a source of current, and a switching means for changing the relationship of the different frequency units of the selector device to the various tone units of the musical instrument. 110

9. In an instrument of the type set forth, an audio frequency selector device, a plurality of locking relays, a switching metronome, a plurality of oscillating devices of audio frequencies, switching means for changing the relationship of the different frequency units of the selector device to the oscillating device, and a source of current. 115

10. In an instrument of the type set forth, an audio frequency selector device, a switching metronome, a plurality of oscillating devices of audio frequencies, switching means for changing the relationship of the different frequency units of the selector device to the oscillating devices and a source of current. 125

11. In an instrument of the type set forth, a source of sound waves operating an audio frequency selector device the various frequency units of which close locking relays when
- 5 in operation, a switching metronome means for opening the locking relays, a plurality of oscillating devices of audio frequencies operated when the locking relays are closed, switching means for changing the relationship of the different frequency units of the selector device to the oscillating device and a source of current.
12. In an instrument of the type set forth, a source of sound waves, an audio frequency selector device operated by the sound waves, a plurality of oscillating devices of audio frequencies having connections enabling them to be operated by the selector device through a switching metronome, switching means for changing the relationship of the various frequency units of the selector device to the various oscillating devices and a source of current.
13. In an instrument of the type set forth an audio frequency selector device and a musical instrument having connections enabling it to be operated by the selector device.
14. An instrument of the type set forth comprising a source of sound waves in operative relation to an audio frequency selector device the various frequency units of which have connections enabling them to operate an oscillating device of various audio frequencies through a switching metronome.
- 35 15. An instrument of the type set forth comprising a source of sound waves in operative relationship to an audio frequency selector device, the various frequency units of which have connections enabling them to operate a musical instrument through a switching metronome.
16. An instrument of the type set forth comprising a source of sound waves in operative relation to an audio frequency selector device the various frequency units of which have connections enabling them to operate an oscillating device of various audio frequencies through an intermittent switching device.
- 45 17. An instrument of the type set forth comprising a source of sound waves in operative relationship to an audio frequency selector device the various frequency units of which have connections enabling them to operate a musical instrument through an intermittent switching device.

In witness whereof, I hereunto subscribe my name this 14th day of May A. D. 1930.

EMORY D. HECOX.
